UNITED STATES PATENT OFFICE.

HOWARD G. BARTLING, OF CHICAGO, ILLINOIS, ASSIGNOR TO PEERLESS PNEUMATIC SYSTEMS, INC., OF CHICAGO, ILLINOIS, A CORPORATION OF ILLINOIS.

SPRAYING CABINET AND APPARATUS.

Application filed November 24, 1922. Serial No. 603,055.

This invention relates to improvements in spraying cabinets and apparatus for use in connection therewith.

The object of the invention is to provide a spray cabinet of such size and construction that the fumes and mist from the spraying will not escape at the sides of the front opening of the cabinet.

Another object consists in the provision of means associated with the spraying cabinet for carrying the apparatus for the control and treatment of air and spraying ingredient.

Another object consists in the provision of new and improved apparatus for the treatment of the air used in spraying with my improved cabinet.

A further object consists in the provision of apparatus for the delivery of varnish or other ingredient.

Still another object consists in the provision of means for the automatic heating and regulating of the heat of the varnish or other ingredient.

These and other objects will be more fully set forth and described in the following specification and shown in the accompanying drawings, in which—

Figure 1 is a front elevation of the cabinet and associated apparatus;

Fig. 2 is a front elevation of the control and treating apparatus shown on an enlarged scale, a portion of the air treatment apparatus being shown in section;

Fig. 3 is a detail of the automatic varnish heat control.

Like numerals refer to like elements throughout the drawings, in which—

10 indicates generally the cabinet having side walls 10^a. The side wall is outwardly flanged, and to it is bolted or otherwise suitably secured the inwardly projecting flange 10^b. This flange prevents escape of spray fumes or mist from the cabinet at the point where they are most liable to escape. In spraying this mist has a tendency to rebound from some of the surfaces being sprayed, and, obviously, the exhaust draft at the edges of the opening is of less effect. By providing this flange I redirect the fumes into the zone of greater effect of the exhauster, or permit deposit of the spraying ingredient upon the flange, with its consequent flow back on to the floor of the cabinet.

55 The front of the cabinet, 10^c, is open, and a

removable shelf 10^d may be provided for the support of the small articles to be sprayed.

The rear wall 10^b of the cabinet 10 has an exhaust port 10^h, which is surrounded by a reinforcing flange 10ⁱ. Mounted in 60 the port 10^h is the rotatable exhaust fan 12, actuatable by any suitable means.

The frontal flange 10^e not only projects laterally inward from the side walls at both sides of the frontal opening, but also desirably projects laterally outward beyond the side walls 10^a, as shown in Fig. 1. Secured to the outwardly projecting lateral portion of this frontal flange 10^e at one side of the cabinet are hinges 16 which support a carrier frame or panel 15, these hinges being arranged as to permit swinging of the frame to the position shown in Figs. 1 and 2 in one position, and to permit swinging back against the side of the cabinet into inoperative position at the other limit of travel.

Carried by the carrier 16 are the air-purifying unit 18, the varnish pressure-controlled unit 19, the air-heating unit 20, the varnish-heating and heat control unit 21, and the spare parts box 22, carrying on its hinged cover a solvent cup or holster 23. These units will be more fully hereinafter described.

In the use of these spraying cabinets, it 85 is customary to use a spray gun 25, or the like, the construction of which forms no part of the instant application. The varnish or other liquid or ingredient supply tube 26 leads to one port of the gun, while the air 90 tube 27 leads to another port, means being provided with the gun for its control and actuation.

The air purifying unit 18 comprises a separating chamber in which may be located 95 any desired means for removing the water, oil or other impurities from the air used for spraying. The air under pressure is supplied to the purifying unit 18 through pipe 30 and purified air is delivered from the 100 purifier 18 by pipe 18^a. Tie rods 18^d serve to secure the heads and cylinder of the purifier in assembled relation.

The pipe 18^a leads to the pipe 20^a, which leads to the air-heating unit 20. A pipe or tube 19^a leads from the pipe 18^a into communication with the flexible tube 31, which, in turn, leads to the varnish barrel 32, through the box 33, and is threaded into 110 the side of the varnish barrel, as shown in

Fig. 1. Interposed in the pipe 19^a is the pressure indicator 19^b and also a pressure-controlling device 19^c of conventional construction, which, by manipulation of the operating handle 19^e, will control the pressure flowing to the varnish barrel. There is also provided in the pipe 19^a a main shut-off valve 19^h and a safety valve 19^f located between the pressure regulator 19^c and the varnish barrel 32. The box 33 is provided with a depending tube 33^a terminating adjacent the bottom of the barrel and in communication at its upper portion with the varnish tube 35. A pressure discharge valve 33^a is located on the box 33 for blow-off of pressure after the use of the varnish. The air pipe 20^a communicates with the air heater unit 20, in which is provided any suitable heating element, such as an electric coil, the terminals 20^b leading through the heater. The tube 27 leads from the air heater to the spray gun, as mentioned above, a shut-off valve 27^a being provided—see Fig. 2. The varnish supply tube 35 leads to the top of the varnish heater 21, which comprises a cylinder, or the like, in which is inserted a suitable heating element, not shown, the terminals 21 leading thereto.

I find it highly desirable and advisable to regulate the heating of the varnish automatically, as conditions may vary from time to time, and manual regulation is not satisfactory. For this purpose I provide a heat-regulating unit, such as shown, for example, in Figs. 2 and 3, consisting of a tube 40 depending into the varnish chamber and filled with a suitable amount of liquid. In communication with this tube, and located thereon, is a Bourdon tube 41, curved or bent, and carrying at its free extremity an insulated pin 41^a. A bracket 42 is provided, adjustable vertically by means of the screw 42^a extending to and threadedly engaging the flange 42^b. The bracket 42 is provided with a projecting flanged arm 42^c, which carries flexible or resilient metallic strips 42^d, 42^e, which are electrically connected with the wires 45, 46 leading to a suitable source of current. The strips 42^d and 42^e are separated by sheets of insulating material 42^f and are provided with metallic contacts 42^g and 42^h. The strip 42^e projects beyond the strip 41^a and overlies the insulated pin 42^a.

When the liquid in the tube 40 expands sufficiently the Bourdon tube 41 has a tendency to uncoil, and the end lifting the pin 41^a will ultimately lift the strip 42^e until contact is broken, and the current supplied to the heating tube 40 will be discontinued until the heat of the varnish has dropped below a predetermined point. By adjustment of the screw 42^a the metallic strips may be raised or lowered and the temperature cut

off or altered accordingly. Means are provided for the indication of the heat, but this feature forms no part of the present invention.

The varnish tube 26 leads from the cylinder 21 to the gun 25, as previously described. A spare parts box 22 is provided having a hinged cover, upon which is mounted an open top or solvent cup 23, into which the spraying end of the gun may be inserted after the conclusion of the spraying operations, the solvent in the cup serving to wash or clean the nozzle of the gun of any varnish or other adhering substance.

In the use of my cabinet, the operator may turn on the current for both the heating and varnish-heating units, swinging the apparatus carrier 15 to the position shown in Fig. 1, where all of the controls are readily accessible and visible during the spraying actuation. This is a very meritorious feature of my invention, increasing, as it does, the ease and efficiency of use of the spraying apparatus.

The safety valve 19^f, being located away from the varnish barrel, is not in danger of being clogged by the varnish or other ingredient, and consequently is free to operate at any desired pressure, thereby eliminating the danger of explosions or destruction of the varnish barrels, as has sometimes occurred in other apparatus.

It will be obvious that my invention is susceptible of modification and alteration; and I do not therefore wish to be restricted to the apparatus and structure shown and described, except as defined in the appended claims.

I claim:

1. A spraying cabinet having a frontal opening formed by an inverted U-shaped flange extending downwardly from the top of the cabinet and laterally inward from each side wall of the cabinet the said top and the side walls being imperforate and adjoining to the said frontal portion; and a suction fan mounted substantially centrally in the rear of the cabinet and arranged for drawing air rearwardly through the cabinet.

2. In combination with a spraying cabinet, a spray means, a supply of spraying ingredient, controlling apparatus, a carrier hingedly secured to said cabinet, said apparatus being carried thereby, and flexible tubing connecting said spraying means and ingredient supply with said apparatus.

3. In combination with a spraying cabinet, a spraying means, a solvent holster carried by said cabinet, said holster being constructed and arranged to permit insertion of said spraying means.

In testimony whereof, I have subscribed my name.

HOWARD G. BARTLING.
